UNITED STATES PATENT OFFICE.

NATHANIEL M. SIMONDS, OF ST. LOUIS, MISSOURI.

WATER-HEATER FOR COOKING-RANGES, &c.

SPECIFICATION forming part of Letters Patent No. 242,383, dated May 31, 1881.

Application filed September 17, 1880. (No model.)

To all whom it may concern:

Be it known that I, NATHANIEL M. SIMONDS, of the city of St. Louis, in the State of Missouri, have invented a certain new and useful Improvement in Water-Heaters for Cooking Ranges, Stoves, &c., of which the following is a full, clear, and exact description, reference being had to the accompanying drawings, making part of this specification.

10 My invention relates to an improvement in those devices which consist of a water-reservoir formed with a horizontal trunk or chamber inserted through the side wall or plate of the fuel-chamber.

15 My improvement consists in providing said trunk or chamber with a horizontal plate to separate the current of cooler water flowing toward the fire from the hotter water flowing back into the tank or reservoir.

20 In the drawings, Figure 1 shows the improvement in vertical section at $x x$, Fig. 2, with parts of the range and hot-water tank in section on the same plane, and parts in elevation. Fig. 2 is a horizontal section of the improvement and water-tank and part of the range at $x' x'$, Fig. 1. Fig. 3 is an end view of the water-trunk from the inside of the tank, showing part of the wall of the tank.

25 A is the range, having side wall, A', and furnace or fire-chamber B. The wall A' is made with an aperture to receive the end C of the water-trunk, which thus forms part of the furnace or fire-wall.

30 D is a flange fitting the outside of the range-wall A', and attached thereto by bolts d, or otherwise, so as to make a sufficiently tight joint. The other end, C', of the water-trunk or chamber is connected to the water-tank F by a flange-joint, or otherwise, and is in open communication with the tank, so that water flows freely from and to the tank, as shown by arrows. I have shown the water-trunk with a flange, D', lying against the outside of the tank, and a collar-plate, D², inside the tank, surrounding the orifice $e e'$, with bolts d' extending through the flange, tank, and collar-plate. The joint between the water-trunk and the tank must be water-tight.

E is the diaphragm or division-plate dividing the water-trunk into two water ways or 50 passages, $e e'$, one beneath the other. The division-plate E does not extend across the whole area of the water-trunk, but there are at the corners orifices $e^2 e^2$ for the ascent of the heated water from the water-way e to that e' . 55 Thus the water flows from the tank to the fire-plate c beneath the division-plate E, and returns to the tank above the division-plate or diaphragm along passage e' .

The diaphragm E may be attached to or in 60 contact with the fire-plate c, or it may be out of contact with it, so as to leave a long and narrow orifice for the upward flow of water across the whole width of the fire-plate.

The division-plate or diaphragm E may be 65 made in one piece with the water-trunk, or may consist of a separate plate or plates inserted therein. My preference is to make it in one piece with the water-trunk. The trunk is inserted through either side or back of fuel or 70 fire chamber.

The diaphragm E may extend any suitable distance into the water tank, receptacle, or chamber F, the most available means for the construction being by a separate plate, E. (See 75 dotted lines in Figs. 1 and 2.)

I have shown the tank F of a cylindrical form, but do not confine myself to any special shape. For instance, it may be of rectangular flattened form extending horizontally, as a 80 steam heating or cooking table.

I claim as my invention—

1. The combination, with the fire-chamber or furnace B and water tank or receptacle F, of the water trunk or chamber C C', with a division, E, therein, substantially as and for the purpose set forth. 85

2. The combination of furnace B, water-trunk C C', and tank F, and the extension-plate E', operating substantially as set forth. 90

NATHANIEL M. SIMONDS.
